UNITED STATES PATENT OFFICE.

WILLIAM R. FOX, OF GRAND RAPIDS, MICHIGAN.

SHIFTING AND BUFFER MECHANISM FOR TYPE-WRITING MACHINES.

1,163,133.

Specification of Letters Patent.

Patented Dec. 7, 1915.

Application filed June 7, 1907. Serial No. 377,752.

To all whom it may concern:

Be it known that I, WILLIAM R. FOX, a citizen of the United States, residing at Grand Rapids, in the county of Kent, State 5 of Michigan, have invented certain new and useful Improvements in the Shifting and Buffer Mechanism for Type-Writing Machines, of which the following is a specification.

10 This invention relates to improvements in typewriters and more especially to improvements in front strike typewriters.

This invention relates particularly to the shifting mechanism for shifting the type 15 bar support and the connected basket of such front-strike typewriters.

The objects of this invention are: first, to provide an improved construction of shiftable type bar support; second, to provide an 20 improved counterbalancing means therefor; third, to provide an improved guiding means for such type-bar support; fourth, to provide improved adjustable stops; and fifth, to provide such improved stops with 25 suitable buffers for absorbing the vibration and avoiding noise.

Further objects and objects pertaining to minor details of construction will definitely appear from the detailed description to 30 follow.

I accomplish the objects of my invention by the devices and means described in the following specification.

The invention is clearly defined and pointed out in the claims.

Portions of a typewriter embodying the features of my invention are clearly illustrated in the accompanying drawing, forming a part of this specification, in which:

40 Figure 1 is a detail view of the parts of a typewriter involved in this invention, portions of the main frame being broken away to show the details of construction; Fig. 2 is an enlarged sectional view of the adjustable 45 stop and buffer and guiding means, partially in section, taken on a line corresponding to line 2—2 of Fig. 1; Fig. 3 is an enlarged detail of one of the adjustable stops, partially in section, taken on a line correspond-

50 ing to line 3—3 of Fig. 2; Fig. 4 is a detail view, partially in section, of the counterbalance and adjusting mechanism, taken on a line corresponding to line 4—4 of Fig. 1; and Fig. 5 is an enlarged detail view of the 55 adjusting means for putting tension on the counterbalance spring, partially in section,

taken on a line corresponding to line 5—5 of Fig. 4.

In the drawing, all of the sectional views are taken looking in the direction of the 60 little arrows at the ends of the section lines, and similar numerals of reference refer to similar parts throughout the several views.

Referring to the numbered parts of the drawing, the main frame 1 is of the usual 65 construction appearing in a Fox visible type-writing machine, which is a front strike machine. The carriage 2 is supported thereon on suitable ball bearings, the said carriage being of the non-shifting type, 70 carrying a platen 3, the general relations of which parts appear in Fig. 1.

The typebar support 4 is provided with a type basket 5 which is secured thereto by suitable means and is movable therewith. 75 The type bar support 4 is carried on a pair of links 6 and a pair of rock shaft arms 7, the links connecting to the upper part and the rock shaft arms 7 to the lower part of the typebar support, one only of each pair 80 being illustrated in Fig. 1, as the opposite pairs are identical and symmetrical.

The links 6 are connected by pivots 9 to the upper rear portion of the frame and the rock shaft arms 7 are carried by the rock 85 shaft 10 arranged transversely through the lower rear part of the frame. A key lever 11 provided with a connecting link 12, connects to an arm 13 on the rock shaft 10. The arm 13 and the arm 7 are integral and 90 preferably connected to the same hub, but of course they may be made in separate pieces.

In a suitable recess on the side of the arm 13 is a screw 14 and on the shaft 10 is a spiral spring 15. At one end of the spring 95 15 and secured thereto is a worm gear 16, turning freely on the rock shaft 10 and engaged by the screw or worm 14, whereby the same can be adjusted. The opposite end of the spring 15 is secured at 18 to a depending hanger or support 17 which supports the center of the rock shaft 10; the upper end of this hanger being secured to the upper part of the frame 1. From this arrangement it will be seen that when the 100 screw 14 is adjusted the tension on the spring 15 can be varied and it can be nicely adjusted so that the entire weight of the typebar support and the attached typebars and typebar basket can be substantially 105 counterbalanced so that there will need be very little pressure applied to the button 110

of the lever 11, making the typebar shift with very light pressure and, at the same time, very promptly, and as the same is counterbalanced by means of the spring, as 5 distinguished from any weight connection, the momentum of the parts is reduced to the minimum.

As heretofore constructed, the shifting of the type-bar support makes a great deal of 10 noise, and it is also desirable to accurately limit and direct the motion of the typebar support. I accomplish this by planing a flat surface 26 on each side of the typebar support, the opposite sides being symmetrical and parallel; and I form stops on the 15 typebar support at 19 and 20, a recess being shaped in each side for that purpose. A bracket or arm 21 is formed on each side of the frame 1 of the machine and extends 20 into the recess I have thus formed in each side of the typebar support. Transversely through this bracket I arrange the screw 27 so that its flat head 28 is adjustable against the flat guiding surfaces 26 to limit and 25 direct the motion, and this is secured in place by the lock nut 29. This makes it possible to adjust this guiding means to locate the typebar support definitely within varying limits. In the top and bottom of this 30 projecting portion or arm 21 I provide adjustable stop screws 22 which are provided with heads 23 having countersunk bores therein, into which I insert disks of sole leather which have been compressed and 35 pounded to make them as compact as possible. This buffer should be very compact so that the typebar carrier is effectively stopped at an unvarying point. I find such compacted sole leather very effective, but 40 equivalent material may be supplied. Boxwood or maple may be used, only such wood, or any wood, is not as durable and consequently not as effective. These supports are adjustable and when placed in the right 45 position are secured there by lock nuts 25, and, by this means, it will be observed that the movements and location of the typebar support can be regulated to a nicety and the compressed sole leather serves to absorb 50 the vibration and avoid any metallic clicking, and, owing to the delicate counterbalance of the parts, a heavy blow is avoided and the buffer that I have provided is able to withstand the necessary wear and 55 tear and is found to be sufficient to absorb largely the vibration and avoid, almost completely, the very objectionable noise owing to the employment of such shifting means.

60 I have shown an arrangement of parts which I have found to be exceedingly effective in use when made in the exact form that I have here illustrated, many hundreds of machines having been provided with this 65 device, so that it has been thoroughly test-

ed. I desire to remark, however, that from my experience I am aware that the form of these various parts can be definitely varied without departing from my invention. I desire to claim the specific form of means, 70 and also to present broad claims that would embrace such modifications.

Having thus described my invention, what I claim as new and desire to secure by Letters Patent is:

75

1. In a typewriting machine, the combination of the main supporting frame; a non-shifting carriage with a platen thereon; a shiftable typebar support arranged beneath and toward the front of said platen, supported on pairs of parallel links and rock shaft arms; a rock shaft carrying said rock shaft arms; a spring counterbalance for said typebar support and connected parts; means for adjusting said counterbalance 80 comprising a screw and worm gear; and a shift lever suitably connected for shifting said typebar support, substantially as described.

2. In a typewriting machine, the combination of the main frame; a non-shifting carriage with a platen thereon; a shiftable type-bar support arranged beneath and toward the front of said platen; a counterbalance therefor; stops on said shiftable support, with a guiding surface between; projecting arms or brackets on the frame of the typewriter, with flat-headed transverse screws to engage the flat guiding surface, with locking means for retaining them in 100 place; and adjustable stop screws in said arms or brackets, having recessed heads containing disks of compressed sole leather or equivalent material, adjustable to limit the motion of the said typebar support and absorb the vibration and avoid the noise, co-acting for the purpose specified.

95

3. In a typewriting machine, the combination of the main frame; a non-shifting carriage with a platen thereon; a shiftable typebar support arranged beneath and toward the front of said platen; a counterbalance therefor; stops on said shiftable support; projecting arms or brackets on the frame of the typewriter; and adjustable 110 stop screws on said arms or brackets, having recessed heads containing disks of compressed sole leather, or equivalent material, adjustable to limit the motion of the said typebar support and absorb the vibration 115 and avoid the noise, coacting for the purpose specified.

120

4. In a typewriting machine, the combination of the main frame; a non-shifting carriage with a platen thereon; a shiftable typebar support arranged beneath and toward the front of said platen; stops on said shiftable support, with a guiding surface between; projecting arms or brackets on the frame of the typewriter, with flat-head- 125

130

ed transverse screws to engage the flat guiding surface, with locking means for retaining said screws in place; and adjustable stop screws on said arms or brackets having 5 recessed heads containing disks of compressed sole leather, or equivalent material, adjustable to limit the motion of the said typebar support and absorb the vibration and avoid the noise, coacting for the purpose specified.

5. In a typewriting machine, the combination of the main frame; a non-shifting carriage with a platen thereon; a shiftable typebar support arranged beneath and toward the front of said platen; stops on said shiftable support, with a guiding surface 30 therebetween; projecting arms or brackets on the frame of the typewriter, flat-headed transverse screws mounted in said arms to engage the flat guiding surface, and locking means for retaining said screws in place, 35 coacting for the purpose specified.

tion and avoid the noise, coacting for the purpose specified.

6. In a typewriting machine, the combination of the main frame; a non-shifting carriage with a platen thereon; a shiftable typebar support arranged beneath and toward the front of said platen; stops on said shiftable support, with a guiding surface 30 therebetween; projecting arms or brackets on the frame of the typewriter, flat-headed transverse screws mounted in said arms to engage the flat guiding surface, and locking means for retaining said screws in place, 35 coacting for the purpose specified.

In witness whereof, I have hereunto set my hand and seal in the presence of two witnesses.

WILLIAM R. FOX. [L.S.]
